UNITED STATES PATENT OFFICE.

BERTHOLD PROSKAUER, OF BERLIN, AND ADOLF IRRGANG, OF BAUMSCHULENWEG,
NEAR BERLIN, GERMANY.

APPARATUS FOR MAKING DENTAL CROWNS AND MOLAR PROJECTIONS.

1,143,432.

Specification of Letters Patent. Patented June 15, 1915.

Application filed April 16, 1913. Serial No. 761,567.

To all whom it may concern:

Be it known that we, BERTHOLD PROSKAUER and ADOLF IRRGANG, citizens of the German Empire, and residing, respectively, at Berlin and Baumschulenweg, near Berlin, Germany, have invented a certain new and useful Improved Apparatus for Making Dental Crowns, Molar Projections, and the like, of which the following is a specification.

Our invention relates to an apparatus for making seamless dental crowns, molar projections and the like, employing as the material for making the matrix the composition consisting of shellac, rubber, rosin or the like. The crown casing is pressed between the matrix consisting of the above-named material and a counter-die held by the aid of a stem in the punch.

Our invention is illustrated in the accompanying drawing, wherein:—

Figures 1 to 3 illustrate a mold which serves for producing a counter-die provided with a stem, Fig. 1 being a top plan view of the lower box, Fig. 2 a bottom plan view of the upper box, and Fig. 3 a longitudinal section through the closed box taken on the line A—B; Figs. 4 to 8 show a stamping apparatus, Fig. 4 being a longitudinal section taken on the line I—K in Fig. 6, Fig. 5 a longitudinal section taken on the line L—M in Fig. 6, and Figs. 6, 7 and 8 cross-sections taken on the lines N—O, P—Q, and R—S, respectively, in Fig. 4; Figs. 9 and 10 show a device for subsequently stamping the contours, and are a longitudinal section, and a cross-section taken on the line T—U in Fig. 4, respectively.

Referring to the drawing, 1 indicates the frame of the lower molding box which is provided with a hollow portion 2 and an edge portion 3. In the latter is a conical recess 4 having therein a groove 5 terminating in a point. By means of dowel pins 6 the upper box 8 having the hole 7 can be applied to the lower box, the said upper box corresponding in its external form with the lower box 1 except that it lacks the groove 5. Into the conical recess 4 of the upper and lower boxes fits a stopper 9 which is preferably provided with a grip 10. The upper and lower boxes may be held together by means of springs instead of by the pins 6.

The counter-die located in the molding box and formed in the manner hereinafter described comprises the stem 4' having the

lug 5' and fitting in a punch 11, the upper end of which is tapered and provided with a head 12. In the middle of the punch 11 is a bore 13, which terminates in a chamber 14. The punch has at its outer periphery a groove 15 for the reception of a guide (see Fig. 5).

The matrix is formed in a cup-like member 16 illustrated in Figs. 4, 5 and 8. The said member preferably consists of a cylinder whose lower end 17 has an aperture 18, and in which a plate 19 can be fitted. In the inside of the stamping member 16 knives can be arranged to which recesses in the extension of the punch 11 must then correspond. Moreover, a setting groove 20 is provided in the chamber 14 of the punch 11 and a guiding groove 21 on the outside of the stamping member 16, the latter groove corresponding to the guiding groove 15 of the punch 11. The lower end 22 of the punch 11 has an external thread, on which a projection 23 having an internal thread can be screwed. The latter is turned at its lower end to form a conical portion 24 and runs out into an annular lip or cutting edge 25.

The crown casings and the like are stamped in a cylinder 26 which is suitably roughened on its outer surface or so formed that it can be readily held by the hand. At about two-thirds of its height the cylinder 26 is provided with two opposite holes 27, 28, through which a pin can be inserted for the purpose of securing the punch 16 so that it projects out of the cylinder 26. In this position the matrix material is inserted, whereupon after the pin has been withdrawn from the holes 27, 28, the punch is lowered into the position shown in Fig. 4.

The cup-like member 29 illustrated in Figs. 9 and 10 for the subsequent stamping of contours will now be described. This member has an aperture 30, and a setting lug 31, and is tapered in its central portion for the purpose of receiving the material serving as the mold, lead being preferably employed.

By means of the described devices the process of making the crowns, etc., can be carried out as follows: The counter-die is first of all provided with a normal stem, independently of its special shape. This is effected by the gypsum replica of the tooth to be provided with a crown and produced

in known manner being first of all reproduced in gypsum in the lower box 1 and in the upper box 8, the stopper 9 being inserted. After the removal of the stopper 5 and of the replica of the tooth a readily fusible metal is poured into the chamber so formed; the counter-die formed in this manner has the stem 4 seen in Fig. 9 with the lug 5', which fits in a corresponding groove 20 of the punch 11. In order to make the matrix the stamping piece 16 is filled in the above described manner with the molding material of the character mentioned, whereupon it is put into its position at the 10 lower end of the stamping cylinder 26. Hereupon the punch 11, carrying at its lower end the counter-die 4', is introduced and moved downward so far that the matrix is produced in the still soft molding material. 15 The position which the matrix and counter-die take up relative to one another is insured during the entire subsequent operation by means of the guiding grooves in the stamping piece 16 and punch 11 and by the 20 guiding lugs on the stamping cylinder 26. In consequence of this, after the cooling and accompanying hardening of the molding material the counter-die and matrix can be removed without hesitation from the stamping cylinder in order to separate them, it being noted that in the case of smooth teeth such separation is effected simply by withdrawing the punch 11, whereas in the case of teeth having overhanging portions the 25 matrix must first be detached. After the casting serving for the production of the dental crown has been lightly struck on the counter-die and cut to the length of tooth, the punch 11 having the projection 23 is inserted into 30 the stamping cylinder 26 and driven down, the crown being thus formed between the matrix and the counter-die. The employed molding material consisting of shellac, rosin, rubber and the like after having cooled becomes sufficiently hard and firm, to press the 35 gold casing between itself and the counter-die without folds, also it has the property of yielding sufficiently under pressure to allow the formation of an intermediate space 40 which suffices to permit the counter-die provided with a gold casing to be again inserted, the pressure exerted by the said projection on the matrix material presses the latter together around the casing for the 45 crown both uniformly and from all sides. The punch is preferably driven down by blows of a hammer but it will be understood, however, that the crowns can be pressed mechanically by means of the mechanically 50 and hydraulically driven presses well known in dentistry. Finally it may be stated that 55 possible unevennesses which might be observed with teeth having molar projections 60

can be rectified by restamping in the auxiliary mold 29 which can likewise be inserted 65 into the stamping casing. It will be understood that the position of its contours which have been struck before the crown casing is inserted in the lead block 32 is secured owing to the setting lugs 31. 70

The apparatus according to our invention can of course be employed not only for manufacturing dental crowns and the like but also for all other small stamping work carried out in dentistry, without regard to the 75 material to be employed.

We claim:—

1. In a device of the character described, the combination with a casing adapted to contain a matrix at one end thereof, of a 80 plunger adapted to reciprocate in the casing and having therein a conically hollowed annular projection for uniformly compressing the matrix on all sides when the plunger is driven into the casing, the end of the 85 plunger in the casing having a recess for receiving a counter-die.

2. In a device of the character described, the combination with a casing adapted to contain a matrix at one end thereof, of a 90 plunger adapted to reciprocate in the casing and having therein a conically hollowed annular projection for uniformly compressing the matrix on all sides when the plunger is driven into the casing, the end of the plunger in the casing having a longitudinally 95 grooved recess for receiving a counter-die.

3. In a device of the character described, the combination of an outer casing, a matrix casing normally at one end thereof, a plunger adapted to reciprocate in the outer casing, an internally conical member mounted on the plunger and adapted to enter into the matrix casing, whereby when the plunger is pressed inward, said member will 100 compress a matrix in the matrix casing. 105

4. In a device of the character described, the combination of an outer casing, a matrix casing normally at one end thereof, a plunger adapted to reciprocate in the outer casing, an internally conical member mounted on the plunger and adapted to enter into the matrix casing, the outer casing having two transverse holes in the wall thereof at such a distance from the other end that said 110 member can be held projecting out of the outer casing by a pin inserted into said 115 holes, for the purpose specified.

In testimony whereof, we affix our signatures in the presence of two witnesses.
